Primary Examiner — Sandra L Morris*(74) Attorney, Agent, or Firm* — Roach Brown McCarthy & Gruber, P.C.; Kevin D. McCarthy(57) **CLAIM**

The ornamental design for a mermaid jet duck, as shown and described.

DESCRIPTION

FIG. 1 is an isometric view of a mermaid jet duck of the applicant's design;

FIG. 2 is a right view of FIG. 1;

FIG. 3 is a left view of FIG. 1;

FIG. 4 is a front view of FIG. 1;

FIG. 5 is a back view of FIG. 1;

FIG. 6 is a top side view of FIG. 1; and,

FIG. 7 is a bottom view of FIG. 1.

The broken lines in FIG. 7 are included for the purpose of illustrating a portion of the bottom that forms no part of the claimed design.

1 Claim, 7 Drawing Sheets(56)
